US00D845271S

(12) **United States Design Patent** (10) **Patent No.:** **US D845,271 S**
Lu et al. (45) **Date of Patent:** **** Apr. 9, 2019**

(54) **INTEGRATED ANNULAR HEADPHONE**

(71) Applicants: **DEXIN ELECTRONIC LTD.,**
Dongguan Guangdong (CN); **DEXIN**
CORPORATION, New Taipei (TW)

(72) Inventors: **Ho-Lung Lu**, New Taipei (TW);
Kuan-Ling Chen, New Taipei (TW)

(73) Assignees: **DEXIN ELECTRONIC LTD.,**
Dongguan, Guangdong (CN); **DEXIN**
CORPORATION, New Taipei (TW)

(**) Term: **15 Years**

(21) Appl. No.: **29/623,715**

(22) Filed: **Oct. 26, 2017**

(51) LOC (11) Cl. **14-01**

(52) U.S. Cl.

USPC **D14/205**; D14/206

Property (USA) Office

(57) **CLAIM**

The ornamental design for an “integrated annular headphone,” as shown and described.

DESCRIPTION

FIG. 1 is a perspective view of an integrated annular headphone showing our new design;

FIG. 2 is a front elevational view thereof;

FIG. 3 is a rear elevational view thereof;

FIG. 4 is a left elevational side view thereof;

FIG. 5 is a right elevational side view thereof;

FIG. 6 is a top plan view thereof; and,

FIG. 7 is a bottom plan view thereof.

The broken lines shown represent unclaimed subject matter
and form no part of the claimed design.

1 Claim, 7 Drawing Sheets
